UNITED STATES PATENT OFFICE.

CHARLES REMHARK, OF SAN FRANCISCO, CALIFORNIA.

GATE-OPERATOR.

1,212,106.

Specification of Letters Patent. Patented Jan. 9, 1917.

Application filed May 15, 1915. Serial No. 28,324.

To all whom it may concern:

Be it known that I, CHARLES REMHARK, a citizen of the United States, and a resident of San Francisco, in the county of San Francisco and State of California, have invented a new and Improved Gate-Operator, of which the following is a full, clear, and exact description.

My invention relates to a type of gate adapted to be employed across a highway, or as a farm gate, and mounted to swing on vertical pivots, the gate being provided with pull cords so arranged as to permit of the gate being opened by a person approaching the same, and closed by said person after having passed through the gate, the pull cords being adapted to be operated by a person afoot, or by a rider or driver, the arrangement being such that the gate may be again closed by the pull cords, after having been opened.

Objects of the invention are to provide a gate of the indicated character, improved in various particulars with respect to its latching means and gate opening and closing means, and with respect to counterbalancing the gate for its easy operation, whereby the opening and closing will be positively effected, and with facility.

Other objects and advantages of my improved construction will appear from the more specific description following.

Reference is had to the accompanying drawings forming part of this specification, in which similar characters of reference indicate corresponding parts in all the views, and in which:

Figure 1 is a perspective view of the gate constructed in accordance with my invention; Fig. 2 is a plan view thereof; Fig. 3 is a fragmentary sectional plan view on the line 3—3 of Fig. 4; Fig. 4 is a transverse vertical section on the line 4—4 Fig. 3; Fig. 5 is a detail in vertical section on the line 5—5 Fig. 3; and Fig. 6 is a detail horizontal section on the line 6—6 of Fig. 4.

In carrying out my invention in accordance with the illustrated example, the gate 10 embodies any approved arrangement of bars, and includes a vertical pivot post 11. The post 11 is stepped at its lower end in a cement base block or footing 12, in which is counter sunk a step bearing 13 receiving the vertical pivot 14 which preferably is formed on the underside of a bearing plate 15 suit-

ably secured to the lower end of the pivot post 11. At the upper end the post 11 has a cap plate 16 and said plate and the post are provided with an orifice to receive a pivot pin 17. Said pivot pin 17 passes downwardly through an overhanging frame member 18 which is rigid with a structure designated generally by the numeral 19, and comprising brace members 19^a as well as vertical posts from which posts the overhanging member 18 extends forwardly to the pivot post 11. The frame 19 includes also a top cross-bar 20^a.

Forming part of the gate 10 is a diagonal brace bar 21 consisting preferably of longitudinal strips disposed at each side of the gate 10. The said diagonal brace 21 passes through the pivot post 11 and is continued beyond the said post in the form of an extension 21^a. Above the extension 21^a a top bar 22 is secured to the same and to the post 11, and finally a rigid prop brace 23 may extend from the lower end of the post 11 at the back to the upper end of the diagonal brace bar 21 and the top bar 22. The elements 21^a, 22 and 23, and certain latch operating means hereinafter explained serve to counterbalance the gate 10 to relieve the pivots of any lateral strains and prevent binding thereof, to permit of the gate being easily turned on its pivots.

On the frame 19 I provide improved latch devices for the gate in the form of a pair of vertically ranging latches 24. The latches 24 are rockably mounted at their lower ends on the frame 19, as, for instance, by pivotally securing the same to a cross-bar 20^b by means of straps 20^c, and said latches are spaced apart so as to accommodate between them the outer end of the top bar 22.

In order to release the top bar 22 from the latches 24 and permit the gate to swing on its pivots, a contact wheel or roller 26 is mounted on a bracket 26^a secured to vertical rocking arms 27 which are pivoted at their upper ends as at 28 to the top bar 22, these arms being operated by pull cords in the manner hereinafter explained. The wheels 26 are adapted to have contact with inclined surfaces of the latches 24, said surfaces preferably presented by wear plates 25. The arrangement is such that a vertical rocking of a bar 27 will press the adjacent latch 24 outwardly to free the arm 22. In order to actuate the latch 24 upon the clos-

ing movement of the gate, the bar 22 of the gate is provided with a horizontal wheel or roller 29 at its outer end adapted to have contact with strike plates 30. One strike 5 plate 30 is provided for each latch 24 and movably engages the same, preferably by a loose vertical pivot 31. At the opposite end each strike plate 30 is hingedly connected as at 32 with the frame 19. The strike 10 plates have wear plates 30^a secured thereto to receive the wear of the roller 29. Each latch 24 is under the influence of a separate retractile spring 33, the said springs being secured at one end to the respective latches 15 24 and at the outer end being secured to the overhanging plate 18, or equivalent fixed member. It is to be noted that the latches 24 are independent, and that each latch at its upper end is rabbeted as at 24^a presenting 20 an upwardly projecting member 24^b that extends above the top cross-bar 20^a of the frame 19, so that said bar 20^a will constitute a stop and limit the movement of the latch under the influence of its spring 33.

25 A system of pull cords is provided in connection with the latch tripping arms 27 and the bar 22, or equivalent element of the gate. At each side of the gate is a pull cord 34 connected at one end with the adjacent vertical 30 rocking arm 27 and passing over a sheave 35 on the bar 22 and over a sheave 36 on a member 37 supported on a wayside post 38 distant from the gate and the frame 19. Thus the pull cords 34 extend in opposite directions along the road from the respective latch operating arms 27. The free depending ends of the pull cords 34 are provided with weights 39 to maintain the pull cords in position under more or less tension and 35 to constitute a hand hold to be grasped by the person desiring to operate the gate. Additional pull cords 40 are provided, these being attached to the gate at opposite sides, preferably to the bar 22, as at 41, and extend in opposite directions over sheaves 42 on members appurtenant to the roadside posts 38, said pull cords 40 having weights 43 similar to the weights 39.

With the above described construction and 50 arrangement of parts, a person approaching the gate 10 from either side, by exerting a pull on the adjacent pull cord 34, will cause the adjacent arm 27 to be rocked upwardly, whereby the roller 26 thereon, by contacting 55 with the inclined surface 25 on the adjacent latch 24, will rock said latch outwardly in opposition to the spring 33 and release the top bar 22 on the gate extension. The initial pull on the cord 34 having released the bar 60 22, a continued pull on said cord will swing the counter balance extension of the gate toward the operator, while the gate proper 10 will move in a direction away from the operator, as will readily be understood. In 65 the swinging of the gate the roller 29 on the

bar 22 will move in contact with the strike plate 30 and maintain the latch in the released position until the gate has swung clear of the same. The gate having been opened, and it being desired to again close 70 the gate, a pull on the pull cord 40 at the opposite side will give a return movement to the counter balance extension, by reason of the said cord 40 being connected with the bar 22. In the closing movement of the 75 gate, as the bar 22 approaches the closed position, the roller 29 thereon will contact with the strike plate 30, and the connection of the latter with the previously operated latch 24 will rock said latch until the bar 22 is received between the pair of latches, whereupon the latch will be closed by the action 80 of its spring 33.

In order to hold the gate latched in the open position, and cause the latch means to 85 be automatically released when the pull cord 40 is caused to give a closing movement to the gate, a gravity latch 45 is pivoted to each wayside post 38. A cord 46, or equivalent extends upwardly from each latch 45 to 90 a flanged roller 47 which rides freely on each pull cord 40. Ordinarily the sag in the cord 40 will permit the latch 45 to gravitate into engagement with members 48 on the top bar of the gate 10. When, however, the cord 40 is made taut by a pull thereon to close the 95 gate, the initial tautening will sufficiently raise the roller 47 to leave the latch 45 out of engagement with the members 48. To prevent the roller 47 from becoming 100 displaced, the housing 49 of said roller is connected by chains 50 or other flexible means with the overhead member 37.

The described construction affords a practical means for carrying my invention into effect, and I would state in conclusion that I do not limit myself strictly to the structural details herein illustrated, since, manifestly, the same can be considerably varied without departing from the spirit of the invention as defined in the appended claims.

Having thus described my invention, what I claim as new and desire to secure by Letters Patent is:—

1. The combination with a swing gate, of 115 separate latches spaced to receive a gate member to retain the latter in the closed position, independent latch operating means on the gate, and actuating means pivotally mounted on the gate connected with the 120 latch operating means and having initial movement to actuate the said latch operating means and serving to open the gate after the release of the latter.

2. The combination with a swing gate, of 125 separate latch members spaced to receive a member of the gate to retain the latter in closed position, latch operating means pivotally mounted on the gate to operate either latch, pull cords extending in opposite di- 130

rections from the gate and connected with the latch operating means, and arranged so that a pull thereon will initially actuate said operating means and then swing the gate, and movably mounted strike plates operatively connected with the latches and disposed in position to be struck by the gate in the closing of the latter.

3. The combination with a gate having a vertical pivot post and a counter balancing extension beyond the post, a latch mounted in position to engage the said extension in the closed position of the gate, latch operating means on the said extension, pull cords extending in opposite directions from the gate and connected with the latch operating means, said pull cords being adapted to actuate the latch operating means and then swing the gate, and a second latch operating means operatively connected with the latch and disposed in position to be actuated by the gate extension in the closing of the gate.

4. The combination with a gate, of a pull cord, operatively connected with the gate, guide means over which the cord runs, means tending to maintain the cord approximately taut, a latch mounted to engage the gate in the open position, and a roller riding on the cord and having operative connection with the said latch, whereby to raise the latch and disengage the same from the gate when a pull is exerted on the cord.

5. The combination with a gate, of a pull cord, operatively connected with the gate, guide means over which the cord runs, means tending to maintain the cord approximately taut, a latch mounted to engage the gate in the open position, a roller riding on the cord and having operative connection with the said latch, whereby to raise the latch and disengage the same from the gate when a pull is exerted on the cord, a relatively fixed element, and flexible means

connecting the said element with the roller, 45 to prevent displacement of the latter.

6. The combination of a swinging gate having an extension at its rear end, a pair of movable and spring pressed latch members between which the extension of the 50 gate projects when the gate is closed, a movable member for operating the latch members, and means connected with the said movable member to first operate it and then swing the gate into open position. 55

7. The combination of a swinging gate having an extension at its rear end, a pair of pivoted and spring pressed latch members between which the extension of the gate projects when in closed position, a pivoted 60 member for swinging the latch members, means connected with the said member to first operate it and thereby release the gate and then swing the gate into open position, and means for operating the latch members 65 on the closing movement of the gate.

8. The combination of a swinging gate having an extension at its rear end, a pair of pivoted and spring pressed latch members between which the extension of the gate 70 projects, a pivoted member carried by the extension of the gate and adapted to engage the latch members to swing them and thereby releases the gate extension, pull cords secured to the pivoted member and extending 75 in opposite directions, said cords serving to first operate the said member and then swing the gate into open position, and means on the gate extension for operating the latch members on the closing movement of the 80 gate.

In testimony whereof I have signed my name to this specification in the presence of two subscribing witnesses.

CHARLES REMHARK.
